UNITED STATES PATENT OFFICE

WILLIAM ROBINSON, OF BROOKLYN, NEW YORK.

ELECTRIC-RAILWAY SYSTEM.

No. 901,381.

Specification of Letters Patent.

Patented Oct. 20, 1908.

Application filed January 26, 1905, Serial No. 242,787. Renewed March 4, 1908. Serial No. 419,196.

To all whom it may concern:

Be it known that I, WILLIAM ROBINSON, a citizen of the United States, and resident of Brooklyn, in the county of Kings and State of New York, have invented a new and Improved Electric-Railway System, of which the following is a specification.

My invention has particular reference to electric railways in which alternating currents are delivered to, and utilized by, electric motor cars or locomotives.

The nature of my invention will be understood from the description which follows, reference being had to the accompanying drawing, which forms a part of this specification, in which

Figure 1 is a diagram illustrating my invention, and Fig. 2 a similar view, but showing a variation in one of the circuits in carrying out the invention.

1, 2, represent a railroad track, and 3 a third rail or working conductor made in sections 4, 5 and 6, separated or insulated from one another, as shown at 7, 8 and 9.

10 represents a high potential alternating current generator, from which proceed the conductors 11, 12 (Fig. 1) to which are connected the step down transformers 13, 14, 15, located at suitable intervals, by the wires 25 47, 48; 49, 50; 51 and 52.

16 represents a direct current generator of comparatively low potential, and 17 a feeder proceeding therefrom, one terminal of said generator being connected by the wire 18 to the return rail 2.

35 The electro-magnets 19, 20, 21, respectively, have one terminal connected to the feeder 17, by the wires 22, 23 and 24, and their opposite terminals to the respective 40 third rail sections 4, 5 and 6, by the wires 25, 26 and 27.

The secondaries 37, 38 and 39 of the transformers 13, 14 and 15 respectively, have one terminal connected to the track return rail 45 sections 57, 58 and 59, respectively, by the wires 28, 29 and 30, and their opposite terminals connected, through the armature levers 31, 32 and 33, to the respective third rail sections 4, 5 and 6, by the wires 34, 35 and 36, as 50 shown.

It will be noted that the circuits through the magnets 19, 20, 21 are normally open, and their armature levers released, consequently the circuits of the secondaries 37, 38 55 and 39 are normally open at the points 40, 41

and 42, the open position being shown in the drawing at 40 and 42 and the closed position at 41.

43 represents a motor car driven by the alternating current motor 44. The car 43 is 60 provided with the controller 45 and the current collecting shoe 46, which makes traveling contact with the sectional third rail 3.

The operation is as follows: When there is no motor car on the section, as shown at the 65 sections 4 and 6, the magnets 19 and 21 are on open circuit as shown, and, consequently, their armatures are released, thus opening the circuits of the transformer secondaries 37, 39 at the contact points 40, 42. When, however, the car 43 enters upon the section, 5, for instance, the closing of the controller circuit 45, as shown, closes circuit between the third rail section 5 and the return rail 2, through the contact shoe 46, the controller 45 and the 70 motor 44, thus closing circuit from the generator 16, through the magnet 20. Said magnet, thus energized, attracts its armature 32, thus closing the circuit of the secondary 38 at the contact points 41. This 75 completes the circuit of said secondary through the third rail section 5, the controller 45, the motor 44 and the service or return track section 58, thus conveying alternating working current of low potential to 80 said motor.

It will be seen that the turning of the controller to the off position simultaneously 85 opens the circuit of the magnet 20, and of the secondary 38, opening the circuit of the latter not only between the third rail section 5 and the service rail section 58, but also at the contact points 41, that is, at two independent points.

The release springs 53 retract the armatures in the usual way when the switch magnets are demagnetized, thus opening the circuits at 40, 41, 42, as described.

The current from the generator 16 is of such low potential that it cannot injure, or be 100 perceived by, any one stepping upon the third rail sections with which it is connected.

When the generator 16 furnishes a direct current to the switch magnets 19, 20, 21, these magnets are of such construction that 105 they cannot be operated by an alternating current, consequently any possible crossing of the alternating current with the circuits of said magnets is technically immaterial, since it cannot affect the proper operation of said 110

magnets. It is possible, therefore, to reduce this system to extreme simplicity in construction and operation. It will be observed, also, that the passing of the car 43 off the 5 section 5 opens the working circuit of the secondary 38 between the track rail section 58 and the third rail section 5 before said circuit is opened at the contact points 41 by the demagnetization of the switch magnet 20, consequently the separation of said points 41 produces no flashing or arcing thereat, since there is no current passing between said points at the instant of their separation. The track rail 2 is shown as a continuous 10 return—in Fig. 1 for the low potential or controlling current only—while the track rail 1 is divided into sections 57, 58, 59, insulated from each other as shown at 61, 62, 63. The 15 secondaries of the transformers, respectively, have one terminal connected to these track sections; thus the secondary 37 has one terminal 28 connected electrically to the track section 57, while one terminal, 29, of the secondary 38 is connected to the track section 58, and one terminal, 30, of the secondary 39 is connected in like manner to the track section 59. Said secondaries have their opposite terminals connected to the third rail sections 4, 5, 6, respectively, as shown. By 20 this arrangement, it will be seen, that the working current from each secondary is confined within narrow or local limits, each secondary, usually, being required to furnish current for only a single section or block; thus leakage of working current incident to 25 long and exposed feeders is avoided, any accident or derangement of the working circuit is confined to the section or block where it occurs, and the voltage of the working current can be reduced to a minimum 30 since it does not have to overcome the resistance of a long and intricate system of feeders from the power house.

Fig. 2 is precisely like Fig. 1, except that in 35 Fig. 2, one terminal of the primaries of the respective transformers is connected to the return rail 2, by the wires 54, 55, 56, instead of to the independent insulated return 11, above described, in which case said return rail 2 is connected by the wire 18 to the terminal 60 of the generator 10, as shown in 40 Fig. 2.

The arrangement shown in Fig. 2 is simpler than that shown in Fig. 1, and dispenses 45 with one insulated live wire; nevertheless, I prefer, the arrangement shown in Fig. 1, especially when the primary current is of very high potential, since by this arrangement the primary circuit is thoroughly insulated from 50 all other parts of the apparatus.

Having thus described my invention, what I claim as new and desire to secure by Letters Patent, is:—

1. An electric railway system comprising 55 a working conductor formed in sections

separated or insulated from one another, a return circuit, an alternating current generator, leaders therefrom, step-down transformers connected to said leaders, the secondaries of said transformers being normally disconnected from said working or contact sections, but arranged to furnish power current thereto, a source of lower potential current than that of said secondaries, a leader therefrom, electro-magnets having, respectively, one 70 terminal connected to said last named leader and their opposite terminals to the respective sections of said working or contact conductor, means for connecting the secondaries of said transformers to the respective 75 sections of said working conductor on the magnetization of said respective magnets, and means for automatically opening the circuits of said secondaries on demagnetizing 80 said respective magnets.

2. An electric railway system comprising a sectional working or contact conductor, a high voltage alternating current generator, leaders therefrom, step-down transformers connected thereto, return circuits, the secondaries of said transformers, respectively, having one terminal connected to said return circuits and their opposite terminals normally disconnected from the sections of said working conductor, but arranged for connection thereto, an independent leader carrying current of lower voltage than that of 90 said secondaries, electro-magnets having their opposite terminals connected to said last named leader and to the respective sections 95 of said working conductor, and switches under control of said magnets, said switches operating to connect the secondaries of said 100 transformers to the sections of said working conductor when the respective magnets are energized and to disconnect said secondaries 105 from said sections when said magnets are de-energized.

3. In an electric railway system, the combination of a working conductor composed of 110 sections electrically disconnected from one another, a source of alternating current supply, leaders or mains therefrom, step-down 115 transformers connected to said leaders and having secondaries normally disconnected from said sections of working conductor, but arranged to transmit power current of lower voltage thereto, an independent leader carrying current of still lower voltage, electro-magnets having their opposite terminals connected to said last named leader and to the 120 respective sections of said working conductor, the circuit through said magnets being normally open, a return circuit, and switches controlled by said respective magnets, said 125 respective switches being arranged to connect the secondaries of said transformers to the respective sections of said working conductor on the magnetization of said magnets and to disconnect said secondaries from said 130

respective sections on opening the circuits of said respective magnets.

4. In an electric railway system, the combination of a working conductor composed of sections electrically disconnected from one another, a source of alternating current supply, leaders or mains therefrom, step-down transformers connected to said leaders and having secondaries normally disconnected from said sections of working conductor, but arranged to transmit power current of lower voltage thereto, an independent leader carrying current of still lower voltage, electro-magnets having their opposite terminals connected to said last named leader and to the respective sections of said working conductor, the circuit through said magnets being normally open, a return circuit, switches controlled by said respective magnets, said respective switches being arranged to connect the secondaries of said transformers to the respective sections of said working conductor on the magnetization of said magnets and to disconnect said secondaries from said respective sections on opening the circuits of said respective magnets, and a car or locomotive traveling in connection with said sectional conductor and provided with an electric controller, the closing of the circuit of said controller operating to close the circuits of said respective magnets and the opening of the circuit of said controller operating to open the circuit of said respective magnets and of the secondaries controlled thereby.

5. In an electric railway system, the combination of a working conductor comprising electrically disconnected sections, an electric locomotive or car traveling in electrical connection therewith, a return conductor, a generator of alternating current of high voltage, leaders or mains therefrom, step-down transformers connected thereto, and arranged to transmit operative current of lower voltage to said locomotive or car through the sections of said working conductor, the transmission of said current being normally interrupted between said transformers and said working conductor sections, an independent leader carrying current of lower voltage than that utilized for operating said traveling motor, electro-magnets having their opposite terminals connected to said last named leader and to the respective sections of said working conductor, the circuit through said magnets being normally open, switches controlled by said respective magnets and arranged to control the transmission of working current to said traveling motor and to disconnect the same therefrom, said traveling motor being arranged to establish electrical connection, successively, between said working sections and the return conductor, and a traveling car controller arranged to open and close circuit through the motor, the opening and closing of said circuit through

the motor operating to simultaneously open and close the switch magnet and working circuits.

6. In an electric railway system, the combination of a working or contact conductor composed of sections separated or insulated from one another, a high voltage alternating current generator, leaders therefrom, step-down transformers connected thereto and having secondaries normally disconnected from said sections of working conductor, but arranged for connection thereto, an independent leader carrying direct current of low voltage, a return circuit, electro-magnets having their opposite terminals connected to said last named leader and to the respective sections of said working or contact conductor, the circuit through said magnets being normally open, and switches controlled by said respective magnets, said switches being arranged to connect the secondaries of said transformers to the respective sections of said working conductor, and to disconnect the same therefrom accordingly as said respective magnets are magnetized or demagnetized.

7. An electric railway system comprising a working or contact conductor formed in sections separated or insulated from each other, a traction rail similarly divided into sections insulated from each other, an alternating current feeder, step down transformers connected thereto and furnishing working current, the secondaries of said transformers being normally disconnected from said working or contact sections but having one terminal arranged for connection thereto, the opposite terminals of said secondaries being connected to the respective sections of said sectional traction rail, a low voltage current feeder, switch magnets having one terminal connected to said feeder and their opposite terminals to the respective working conductor sections, said magnets being arranged to control the completion of electrical connection between said working conductor sections and the secondaries of said transformers, accordingly as said magnets are magnetized or demagnetized.

8. In an electric railway system, an alternating current generator, step down transformers connected thereto, a sectional working or contact conductor, a traction rail divided into sections insulated from each other, the secondaries of said transformers having one terminal connected to said traction rail sections and their opposite terminals normally disconnected from said contact sections but arranged for connection with, and to furnish working current to, said sections, a low potential direct current feeder, switch magnets having one terminal connected thereto, and arranged for operation by direct current, said magnets having their opposite terminals connected to said respective con-

- tact or working sections, and arranged to control the connection of the secondaries of said transformers to said contact sections, and their disconnection therefrom.
9. In an electric railway system, an alternating current feeder, step down transformers connected thereto, their secondaries furnishing working current, a working or contact conductor formed in sections separated or insulated from one another, a traction rail formed in corresponding sections separated or insulated from one another, the secondaries of said transformers being normally disconnected from said working or contact sections but arranged for connection thereto, 15 the opposite terminals of said secondaries, respectively, being connected to the respective sections of said traction rail, means for connecting said secondaries, respectively, to said respective working sections when a car 20 or train enters upon said sections, the respective sections of the traction rail forming returns for the secondaries of said transformers connected thereto.
